UNITED STATES PATENT OFFICE.

VINCENT BENDIX, OF CHICAGO, ILLINOIS.

ENGINE-STARTER.

1,274,369.

Specification of Letters Patent.

Patented Aug. 6, 1918.

Application filed August 14, 1916. Serial No. 114,896.

To all whom it may concern:

Be it known that I, VINCENT BENDIX, a citizen of the United States, residing at Chicago, in the county of Cook and State of 5 Illinois, have invented certain new and useful Improvements in Engine-Starters, of which the following is a specification.

My invention relates to that type of engine starter exemplified in patents heretofore issued to me, for instance Patent No. 10 1,146,992, issued on July 20, 1915, which 15 starter is characterized by a prime mover such as an electric motor, and a transmission or drive for transmitting the power or motion 20 of the motor by means of a screw shaft device to a member of the engine, such as the fly wheel thereof. This transmission or drive comprises a screw shaft operated either directly or indirectly by the electric 25 motor and a driving member such as a pinion mounted on such shaft for longitudinal movement thereon and rotary movement therewith. My invention pertains more particularly to the construction of this pinion, 30 and the object thereof is to improve the action thereof on the screw shaft, particularly that action which takes place after the engine has started on its own power and has automatically demeshed the pinion from the fly wheel.

In the automatic demeshing of the pinion from the fly wheel the pinion, after moving longitudinally on the screw shaft in this demeshing operation, pauses or stops momentarily after having cleared the face of the fly wheel a slight distance and rotates with the screw shaft until such shaft has slowed down, whereupon the pinion will travel longitudinally to home position along the screw 40 shaft, but with slight force. This peculiar coöperation between the pinion and screw-shaft also has the effect of holding the pinion toward its retracted or home position, and tends to prevent its advance movement 45 against the fly-wheel in the event, after the engine has started on its own power, the armature shaft of the electric motor should continue to be rotated rapidly due to inadvertently keeping the current closed on 50 the motor. This pausing or momentary stopping of the pinion on the screw-shaft is due to a binding effect between the threads of the shaft and pinion due to the centrifugal action of the weight arranged at one 55 end of the pinion and projecting from one

side of a vertical plane passing through the point of support of such weight and pinion with respect to the screw-shaft, the centrifugal action tending to draw the weight in a plane of rotation coincident with said vertical plane. This vertical plane is represented in Figure 1 by the dotted line $a-a$, and the outer plane by the dotted line $b-b$. The object of the present invention is to obtain the proper or correct binding effect of the 60 pinion on the screw-shaft which is done by the construction and relationship of pinion and weight as hereinafter described. Speaking in general terms, I accomplish this object, in the broader aspect of my invention, by 65 locating the weight at one end of the pinion, being the end opposite the end which initially meshes with the engine member by terminating the internal threads of the pinion short of the inner side thereof, that is, 70 the end on which the weight is mounted, thereby providing an unthreaded portion in the bore of the pinion which overhangs the shaft so that the point of support of the weight end of the pinion with respect to the 75 shaft and the weight is the initial thread, so that the weight is necessarily located in a plane at one side of a vertical plane passing through such point of support. In practice, it is found that a certain relation 80 exists between the amount of the weight, and consequently the force of the centrifugal action, and the amount of the counterbore, it being possible to reduce the amount 85 of the weight by increasing the counterbore. 90

In the drawing, Fig. 1, is an elevation partly in section of a transmission or drive embodying my invention, and Fig. 2 a central longitudinal section of the pinion.

Inasmuch as my invention concerns only 95 the transmission or drive of an engine starter, which may be operated either directly or indirectly by any prime mover, such as an electric motor, I have shown merely such drive, with the exception that 100 I have shown in addition the extended armature shaft 1 of an electric motor as in the case of a direct drive between the prime mover and this transmission. The armature shaft 1, is secured by means of a bolt 1^a to the driving member or collar 2, which is operatively connected by means of the coiled spring 3 with a driving collar 4^a, which is preferably an integral part of the screw-shaft. This screw-shaft is provided at its 110

2
outer end with a stop-nut or collar 5. Upon the screw-shaft is mounted a driving member, which is in the form of a pinion 6, screw-threaded upon the screw-shaft by means of its internal threads 6^a, with the result that such pinion is capable of moving longitudinally on the screw-shaft, and also rotarily therewith. When the pinion is advanced, that is, moved to the right in Fig. 10 1, it meshes with the teeth 7^a of an engine member, such as the fly-wheel 7 of the engine to be started.

The pinion is provided at one end, which is the end opposite the end which meshes 15 with the fly-wheel, with a weight 8, which is here shown as forming a part of the disk 8^a. In practice the weight constitutes a flange occupying one-half of the circumference of the disk and extending therefrom laterally and at right angles and consequently at right angles to the end of the pinion.

The bore of the pinion is provided with screw threads 6^a for only a portion of its 25 length, such threads stopping short of the weighted end of the pinion. As a result there is a portion of the bore at 6^b which is not provided with threads, and which overhangs the screw-shaft, so that the first 30 point of support of the pinion is at the first thread, as at 6^c, with the result that in its rotation, the weight 8 tends to move into a plane of rotation coincident with a vertical plane passing through point 6^c, thereby 35 causing a cocking of the pinion and a binding thereof on the screw-shaft. The proper action is obtained and controlled by a proper relation between the amount of the weight and the depth of the counterbore, such counterbore increasing the centrifugal leverage 40 on the cocking action of the pinion, and consequently the binding effect thereof on the shaft.

I claim:

45 1. In a drive for an engine starter, the combination of a rotatable screw member, and a member screw-threaded thereon and capable of longitudinal movement thereof and rotary movement therewith, said second 50 mentioned member being weighted on one end and on one side of its axis of rotation and having screw threads for only a portion of its length.

2. In a drive for an engine starter, the 55 combination of a rotatable screw-shaft, and a member screw-threaded thereon and capable of longitudinal movement thereof and rotary movement therewith, said member having a weight on one end thereof and on 60 one side of its axis of rotation and having internal screw-threads extending only par-

tially through its bore, leaving the unthreaded portion at its weighted end.

3. In a drive for an engine starter, the 65 combination of a rotatable screw-shaft, and a member screw-threaded thereon and capable of longitudinal movement thereof and rotary movement therewith, said member having at one end a weight arranged on one side of the axis of rotation of such member and located on one side of a plane extending at right angles to the longitudinal axis of the shaft and running through the point of support of the weight and said member on the shaft, whereby the centrifugal action 70 of the weight in the rotation of said member tends to move the plane of rotation of such weight into a plane coincident with said plane passing through said point of support.

4. In a drive for an engine starter, the 75 combination of a rotatable screw-shaft, and a member screw-threaded thereon and capable of longitudinal movement thereof to engage a part of the engine to be started and capable of rotary movement therewith, said member being weighted at the end opposite its engaging end and having its internal screw-threads extending only partially 80 through its bore, such threads stopping short of the weighted end of said member.

5. In a drive for an engine starter, the 85 combination of a rotatable screw-shaft, and a pinion screw-threaded thereon and capable of longitudinal movement thereof and rotary movement therewith, said pinion having internal screw-threads extending only 90 partially through its bore leaving an unthreaded portion at that end opposite its engaging end, said pinion also having a weight located at its opposite end and arranged on one side of its axis of rotation.

6. In a drive for an engine starter, the 95 combination of a rotatable screw-shaft, a pinion screw-threaded thereon and capable of longitudinal movement thereof to engage a member of the engine to be started, and capable of rotary movement therewith, said pinion having internal screw-threads extending only partially through its bore and stopping short of that end which is opposite the engaging end thereof, and a weight depending from that end of the pinion opposite its engaging end and arranged on one side of a plane located at right angles of the axis 100 of rotation of the pinion and passing substantially through that end of the screw-thread adjacent the weighted end of such pinion.

VINCENT BENDIX.
